ABSTRACT

Methods and apparatus for applying opposite polarity, equal magnitude charging currents to a surface to be charged are provided according to the present invention. In accordance with one embodiment of the present invention at least two corotrons are energized by a floating power supply exhibiting substantially constant current characteristics. The positive terminal of the floating power supply is connected to a coronode of one of the at least two corotrons while the negative terminal of the floating power supply is connected to the coronode of another one of such at least two coronodes. Additionally, the shields of each of such at least two corotrons are interconnected through a current limiting impedance so that current flow between the shields of the at least two corotrons is maintained within a selected range whereupon the ion charging current produced by each of the corotrons is maintained at substantially uniform magnitude levels.

**METHODS AND APPARATUS FOR OPERATING PAIRED
COROTRONS OF OPPOSITE POLARITY**

This invention relates to electrostatic charging apparatus and more particularly to improved methods and apparatus for applying uniform, equal and opposite corona charging currents to a surface to be charged such as those conventionally employed in electrophotographic processes and the like.

In U.S. Letters Pat. No. 3,244,083, as issued to R.W. Gundlach on Apr. 15, 1966 and assigned to the Xerox Corporation, there are disclosed novel methods and apparatus for applying a charge to a photoreceptor structure having an electrostatic image formed thereon so that such operations as image transfer or tacking and stripping can be accomplished without distortion or destruction of the electrostatic image formed on the photoreceptor. As set forth in U.S. Letters Pat. No. 3,244,083, supra, the methods and apparatus disclosed therein essentially contemplate modes of corotron operation wherein at least two corotrons are energized by a floating power supply. The shields of the two corotrons utilized are interconnected and the positive terminal of the power supply utilized is connected to a coronode of one of the corotrons while the negative terminal of such power supply is connected to the coronode of the other corotron. Since no point in the resulting corotron circuit configuration is grounded, it can be demonstrated that at any given instant of time the positive ion charging current delivered to a common moving surface, such as a selenium drum, by the positively connected corotron must be exactly equal to the negative ion current delivered to such moving surface by the negatively connected corotron. The mode of operation thus taught in U.S. Letters Pat. No. 3,244,083, supra, is highly advantageous because in image transfer operations or tacking and stripping operations, if it is assumed that a neutralizing charging current which is equal in magnitude but opposite in polarity to that relied upon in the transfer of an image to a moving surface or in the tacking portion of an operation is utilized upon completion of the transfer or tacking step, it will be immediately appreciated by those of ordinary skill in the art that the medium to which such image has been transferred or the medium to be stripped may readily be removed, due to its electrostatically neutral state, from the surface on which the image was initially formed or on which the medium was tacked without any sparking or other deleterious electrostatic effects occurring. This is highly desirable because sparking and the like will distort or destroy the image present on a moving surface such as a selenium drum and hence the avoidance of such distorting phenomena would allow subsequent image transfers from the same moving surface without necessitating a repetition of the entire electrophotographic process relied upon in the formation of the initial image for each transfer desire.

Unfortunately, in the operation of the invention disclosed in the above identified patent, the operational advantages theoretically predicted by the use of equal and opposite charging currents in image transfer or tacking and stripping operations have not been fully realized because although equal and opposite charging currents are delivered at each instant of time from the positively and negatively connected corotrons to a common moving surface, the same portions of such moving surface do not receive equal and opposite charging currents and accordingly are not rendered electrostatically neutral whereby deleterious electrostatic effects do occur during the separation or stripping of the image transfer material or tacked medium. Detailed study of the operation of the electrostatic charging methods and apparatus disclosed in U.S. Letters Pat. No. 3,244,083, supra, has indicated that the problem area of operation which precludes the actual operation of the charging apparatus taught therein from closely approximating the theoretically predicted results is that even though at any given instant the charging current produced by the positively and negatively connected corotrons must be equal and opposite, they need not be uniform over a predetermined time interval. Thus, as different discrete portions of the surface to be charged are in a charging relationship with the

positively and negatively connected corotrons at a given instant, there is no requirement in the teaching of U.S. Letters Pat. No. 3,244,083, supra, that the negatively connected corotron will apply charging current to a discrete portion of a surface to be charged which is equal in magnitude to the positive charging current received by such discrete portion of the surface at a preceding instant when such discrete portion of the surface to be charged was in a charging relationship with the positively connected coronode. Therefore, the practical problems associated with charging a surface in relative motion with two displaced charging stations, as represented by the positively and negatively connected corotron configuration taught in U.S. Letters Pat. No. 3,244,083, supra, precludes the actual neutralizing results achieved in the use of apparatus employing the teaching therein from approaching the theoretically predicted results because the charging current produced by each of the corotrons need not be maintained at uniform levels. Thus, simply stated the problem is that while the two ion currents produced at the oppositely connected corotrons must be equal in magnitude, such currents do not have to be constant or uniform when the teachings of U.S. Letters Pat. No. 3,244,083, supra, are employed.

In the operation of corotron devices, as stated in my copending application Ser. No. 108,302, filed on an equal date herewith, the actual ion current produced at the coronode is a function of both the voltage applied between the coronode and the surface to be charged and the current flowing in the shield. Furthermore, as will be apparent from the above, the ion charging current delivered from the coronode to a surface to be charged is also a function of the potential level of the surface to be charged as seen by the coronode. Thus, in a multiple corotron charging configuration such as taught in U.S. Letters Pat. No. 3,244,083, supra, not only do the magnitude variations charging currents produced by the positively and negatively connected corotron configurations result in inaccurate levels in the magnitude of the neutralizing charge applied by the second corotron of a pair, but in addition thereto, the variations in the charging current produced by the first corotron of such pair will result in charge variations on the surface of the medium being charged and these charge variations thus caused by the first corotron will result in further variations in the charging current delivered by the second corotron of the pair due to the variations in charge seen by the coronode of such second corotron. Thus, the variations in charging current produced in a multiple corotron configuration such as taught in U.S. Letters Pat. No. 3,244,083, supra, have a cumulative effect from the standpoint of the inability to achieve the delivery of a charging current from the second corotron of the pair having an appropriate magnitude to precisely neutralize the tacking or image transfer charge applied by the oppositely connected first corotron; and, it is this cumulative effect which results in a substantial disparity in the charging current delivered by the positively and negatively connected corotron configurations taught by the subject patent. This disparity, it should be noted, is particularly pronounced at the leading and trailing edges of the image area on the surface to be charged and acts to preclude the removal or stripping of the image transfer or tacked member from the surface to be charged with essentially no net charge associated therewith.

Therefore, it is a principal object of this invention to provide methods and apparatus for operating paired corotrons which are oppositely connected to a common supply in a manner such that substantially uniform charging currents which are equal in magnitude but opposite in polarity are produced thereby. Various other objects and advantages of the present invention will become clear from the following detailed description of an exemplary embodiment thereof, and the novel features will be particularly pointed out in conjunction with the claims appended hereto.

In accordance with the teachings of the present invention methods of corotron operation and apparatus therefor are provided wherein at least two corotrons are energized by a

floating power supply exhibiting substantially uniform current characteristics, the positive terminal of the floating power supply is connected to a coronode of one of said at least two corotrons while the negative terminal of said floating power supply is connected to a coronode of another one of said at least two corotrons, the shields of each of said at least two corotrons are interconnected through current limiting resistor means so that current flow between the shields of said at least two corotrons is maintained within a selected range whereupon the ion charging current produced by each of said corotrons is maintained at substantially uniform magnitude levels.

The invention will be more clearly understood by reference to the following detailed description of an exemplary embodiment thereof in conjunction with the accompanying drawing in which:

The FIGURE is a schematic representation of an exemplary embodiment of paired corotron charging apparatus in accordance with the teachings of the instant invention.

Referring now to the drawing, there is shown a schematic representation of an exemplary embodiment of paired corotron charging apparatus in accordance with the teachings of the present invention. The embodiment of the present invention illustrated in the Figure comprises first and second corotrons 1 and 2 connected to a floating power supply 3 and the resulting paired corotron charging apparatus is disposed in a charging relationship with a medium 4 to be charged. The structure of the first and second corotrons 1 and 2 shown in the Figure may be entirely conventional and comprises a coronode 5 and 6 disposed in a predetermined relationship with the medium 4 to be charged and a shield 7 and 8, respectively, associated with its respective coronode 5 and 6. The coronodes 5 and 6, whose end views are illustrated in the Figure, may take the form of a fine strand of conductive wire disposed longitudinally across the width of the medium 4 to be charged and spaced an appropriate distance therefrom. The coronode wires 5 and 6 would normally be insulated from their respective shields 7 and 8 positioned thereabout by terminal means (not shown) associated with the end portions thereof in the well-known manner shown for instance in U.S. Letters Pat. No. 3,244,083, supra. Although only a single coronode 5 and 6 has been illustrated for each of the corotrons 1 and 2, respectively, it will be apparent to those of ordinary skill in the art that multi-coronode corotrons may be relied upon in applications where it is desired to increase the uniformity of the charging current along the width of the medium to be charged. Similarly, the shields 7 and 8 may take the conventional form of conductive material having a selected configuration disposed in the longitudinal direction in a predetermined relationship with the coronodes 5 and 6, respectively, and fixedly positioned at a selected distance therefrom. Although any of the well-known shield configurations illustrated or discussed for instance in U.S. Letters Pat. No. 2,879,395, to L.E. Walkup and assigned to the Xerox Corporation, may be relied upon in the practice of the instant invention, half-round shield configurations have been illustrated as exemplary; it being noted that such shield configurations are desireable because they tend to keep the coronodes associated therewith cleaner during the continued operation thereof and maintain the charging current produced by a given coronode more uniform with time.

The coronode 5 of the first corotron 1 is connected through the impedance means R_1 to one terminal of the high potential power source 3 while the coronode 6 of the second corotron 2 is connected to an opposite polarity terminal of the high potential power source 3. The high potential power source 3 may take the form of a DC supply having the positive terminal thereof connected to one of the coronodes 5 or 6 while the negative terminal thereof is connected to the other coronode 6 or 5. Alternatively, an AC or pulsed DC source of potential may be relied upon depending on the nature of the charging operation selected. In any event, neither of the terminals of the high potential power source 3 is grounded and preferably,

the high potential power source 3 is insulated in the manner described in U.S. Letters Pat. No. 3,244,083, supra, so that the high potential power source 3 is maintained in a clearly floating posture with respect to ground. Additionally, the high potential power source 3 should preferably exhibit a peak-to-peak terminal voltage in the range of approximately (9-20KV) and be capable of supplying current on a continuous basis in the range of (90-400 μ A). Although the precise electronic configuration relied upon for the high potential power source 3 forms no part of the present invention, any of the high potential power source configurations mentioned in U.S. Letters Pat. No. 3,244,083, supra, clearly may be relied upon. The impedance means R_1 interposed between one terminal of the high potential power source 3 and the coronode 5 may take the form of an ordinary resistor which exhibits a value of resistance which is large compared to the dynamic impedance of the corotrons 1 and 2 so that regardless of any variation in the dynamic impedance of the corotrons 1 and 2, the load seen by the high potential power source 3 is essentially constant and a substantial portion of the voltage drop takes place across the resistor R_1 . As the dynamic impedance exhibited by conventional corotrons, such corotrons 1 and 2 presently under discussion herein, is usually in a range of from 0.25-10 megohms, the value of resistance manifested by the impedance means R_1 will be in a range of from (10-100 M Ω). Therefore, it will be appreciated by those of ordinary skill in the art that the impedance means R_1 and the high potential power source V_1 act in combination to form a constant current source for supplying a substantially constant current to the coronodes 5 and 6. As an alternative to using the combination of a high potential power supply and a large value resistance in series therewith, it will be obvious to those of ordinary skill in the art that a highly regulated power supply designed to function as a constant current source could be substituted therefor. Such constant current supplies are well known and may be regulated either electronically or by conventional loading techniques.

The shields 7 and 8 of each of the corotrons 1 and 2, respectively, are interconnected according to this embodiment of the present invention through a current limiting impedance means R_2 . The function of the current limiting impedance means R_2 is to ensure that the current flowing between the shields 7 and 8 is maintained above a value of approximately 1 μ A/in. of corotron length so that ion charging current from the coronode may be initiated at a lower threshold value of voltage between the coronodes and the surface to be charged while such current limiting impedance means R_2 additionally acts to limit the current flowing between shields 7 and 8 below a predetermined level so that corona charging takes place in a highly efficient manner since the voltage level automatically established across the impedance means R_2 prevents all but a small portion of the ion charging current produced by the coronodes 5 and 6 from being diverted to the shields 7 and 8. The manner in which current flow in the shield above a predetermined minimum value reduces the threshold value of voltage necessary between a coronode and a surface to be charged to initiate ion charging current flow from the coronode as well as the manner in which such shield current establishes a highly efficient range of corotron operation by precluding ion charging current from being diverted to the shield is set forth in detail in my copending application Ser. No. 108,302, filed on an equal date herewith. Therefore, for the purpose of the description of the instant invention, it is sufficient to appreciate that when a current flow equal to or greater than one microampere per inch of corotron length is established between the shields 7 and 8, the threshold value of voltage at which corona charging current is produced at the coronodes 5 and 6 is substantially reduced while the value of the impedance means R_2 and the voltage drop thereacross precludes corona charging current from being diverted to the shield thereby requiring the vast majority of the ion charging current produced by the coronodes 5 and 6 to be delivered to the surface to be charged. As the current flow between the

shields 7 and 8 is increased, improved charging characteristics are observed until the shield current reaches a value of approximately $10 \mu\text{a/in.}$ at which point no further improvement is observed in the characteristics. Therefore, the value of the impedance means R_2 is preferably selected at a value such that the resistance exhibited thereby maintains the current flow between shields 7 and 8 at a value in the range of from $1-10 \mu\text{a/in.}$ of corotron length. The value of the resistance to be exhibited by the impedance means R_2 may be experimentally achieved by varying the impedance thereof until the desired current flows in the shield loop and for this reason the impedance means R_2 is illustrated as a variable resistance device in the Figure. Alternatively, the value of resistance to be exhibited by the current limiting impedance R_2 may be calculated using conventional techniques as the value of the impedance means R_1 is known and the dynamic impedance exhibited by the first and second corotrons 1 and 2 may be determined. Regardless of the technique employed, the value of resistance exhibited by the current limiting impedance means R_2 will ordinarily fall within the range of $(100-500 \text{ M}\Omega)$ depending upon the other parameters exhibited by the embodiment of the invention illustrated in the Figure. Thus it is seen that according to the embodiment of the instant invention, the basic corotron configuration discussed in U.S. Letters Pat. No. 3,244,083, supra, has been altered so that a floating constant current source is relied upon to supply charging current to each of the coronodes 5 and 6 while a current limiting impedance means R_2 is interposed in the connection between the shields 7 and 8 so that current flow therebetween is maintained within predetermined limits.

The resulting corotron configuration illustrated in the Figure is disposed in a charging relationship with a medium 4 to be charged. Although the charging configuration illustrated in the Figure may be relied upon for tacking and stripping operations involving any insulating material or in image transfer operations as aforesaid, an image transfer application of the instant invention has been depicted in the Figure in order to illustrate an exemplary mode of operation of the present invention. Accordingly, in the Figure, the medium 4 will here take the form of a transfer member to which a developed electrostatic image is to be transferred. The medium 4 may thus comprise a sheet, web or drum formed of suitable transfer material such as paper, plastic or any of the other well known materials conventionally employed as transfer materials and is disposed proximate to a photoreceptor 9 having a developed electrostatic image formed thereon. The photoreceptor 9 may take the form of a sheet, web or drum formed of suitable photoconductive materials such as selenium, dispersions thereof or the like which may be overcoated on a conductive or nonconductive substrate. The materials relied upon in the formation of the photoreceptor 9 form no part of the instant invention and thus it is here sufficient to state that the photoreceptor 9 may take any of the well-known forms of structures which admit of the formation of a latent electrostatic image upon the application of electrophotographic processes thereto. A partial listing of suitable photoconductive materials which may be used in the formation of the photoreceptor 9 may be found in my copending application Ser. No. 108,302 filed on an equal date herewith.

The photoreceptor 9, as aforesaid, has a developed electrostatic image thereon which ordinarily would be formed by conventional electrophotographic processes not associated with the corotron charging configuration depicted in the Figure. For instance, a latent electrostatic image would be initially formed by subjecting the photoreceptor to conventional electrophotographic processing steps such as sensitizing the photoreceptor by the application of an electrostatic charge thereto and selectively exposing the photoconductive portion of such photoreceptor 9 to electromagnetic radiation from a light and dark pattern representing the image to be formed. Thereafter, the photoreceptor 9 having the thus formed latent electrostatic image thereon could be developed or further charged and then developed to render the latent electrostatic

image formed viewable. The development of the electrostatic latent image could be accomplished by such well-known techniques as cascade development, as described in U.S. Letters Pat. No. 2,618,551, to L. E. Walkup, where a mixture of toner particles are applied to the surface and will selectively adhere to the surface area of the photoreceptor 9 in accordance with the latent electrostatic image present thereon or alternatively any of the other well-known development techniques such as powder cloud development, brush development, loop development, magnetic development or the like could be used. Furthermore, the foregoing processing steps or other electrophotographic processing steps well known to those of ordinary skill in the art could be carried out in the form of a continuous process, as would be the case if the photoreceptor 9 was in the form of a drum or endless web having apparatus for carrying out each of said steps disposed about the periphery thereof, or alternatively as a series of discrete steps as would be the case if the photoreceptor 9 was in the form of a sheet or web which was conveyed past a series of processing stations. Thus, regardless of the electrophotographic process relied upon, the photoreceptor 9 having a developed latent image thereon is provided prior to the image transfer step depicted in the Figure.

After the photoreceptor 9 has a latent electrostatic image formed thereon and such latent electrostatic image is developed, the transfer member 4 is brought into a proximate relationship therewith so that the transfer member 4 may be charged whereupon the toner particles will be transferred from the surface of the photoreceptor 9 to the surface of the transfer member 4 and thereafter an equal and opposite charge is applied to transfer member 4 in accordance with the teachings of the present invention so that such transfer member may be stripped from the photoreceptor 9. In the Figure, the latent electrostatic image formed on the photoreceptor 9 is indicated by the positive charges proximate to the surface thereof and the dots intermediate the adjacent surface of the photoreceptor 9 and transfer member 4 indicate toner particles adhered to appropriate portions of such surface areas. Although in the Figure positive charges have been relied upon to indicate the charge pattern associated with the latent image formed and toner particles have been indicated as attracted to such positive charges, it will be obvious to those of ordinary skill in the art that a negative charge pattern may be relied upon in the formation of the latent image by altering or reversing the polarity of the initial sensitizing charge utilized in the electrophotographic process and either positively or negatively charged toner particles may be utilized depending upon whether or not a positive or negative image configuration on the photoreceptor is desired. The transfer member 4 is brought into contact with the surface of the photoreceptor 9 just prior to the transfer operation and the transfer member 4 and the photoreceptor 9 are maintained in relative motion with respect to the first and second corotrons 1 and 2 illustrated in the Figure. This may be accomplished by any of the techniques well known to those of ordinary skill in the art, for instance, if the photoreceptor 9 takes the form of a rotating drum, the paired corotron configuration illustrated in the Figure would represent a charging station located about the periphery of such drum while the transfer medium could take the form of a moving web proximate to the portion of the photoreceptor depicted in the Figure and having a supply reel positioned to the right of the second corotron 2 and a take-up reel located to the left of the corotron 1. Another obvious way of arriving at the desired result is to rely upon a web or sheet form of photoreceptor 9, disposing a web or sheet form of transfer member thereon after the latent electrostatic image is formed and developed and then either conveying the photoreceptor 9 having the transfer member 4 thereon past the corotrons 1 and 2 or alternatively adapting the paired corotron configuration to be displaced in a direction from left to right across the surface of the transfer member 4. Thus, regardless of the techniques employed, it will be seen that a photoreceptor 9 having a developed latent electrostatic image

thereon and a transfer member 4 proximate to the charged surface thereof are placed in relative motion and in a charging relationship with the paired corotron charging configuration according to this invention in the image transfer application of this invention illustrated in the Figure.

The operation of the embodiment of this invention illustrated in the Figure will be set forth below under the assumption that a transfer of the developed image from the photoreceptor 9 to the transfer member 4 is to be accomplished and thereafter the transfer member 4 is to be stripped from the photoreceptor 9. Accordingly, the polarities of the ion charging current discussed below will be those appropriate for accomplishing image transfer and stripping for the toner image illustrated; however, it will be readily appreciated by those of ordinary skill in the art, that either of the coronodes 5 and 6 may produce a positive or negative ion charging current depending upon the polarity of the connection of the high potential power source 3 selected. Furthermore, for the purposes of the description of this invention which follows, it will be assumed that the photoreceptor 9 having the transfer member 4 disposed thereon is adapted for displacement from right to left with respect to the first and second corotrons 1 and 2.

In the operation of the embodiment of this invention illustrated in the Figure, negative toner particles are relied upon in the development of the latent electrostatic image on the photoreceptor 9 and hence a direct transfer operation will require that positive charging be carried out by the second corotron 2 while negative charging is carried out by the first corotron 1. Therefore, where these conditions obtain, the high potential power source 3 will be connected in such manner that the positive terminal thereof is connected to the coronode 6 while the negative terminal of the high potential power source 3 is connected to the coronode 5. With the high potential power source 3 connected in the above mentioned polarity the second corotron 2 will deliver positive ion charging current to the surface of the transfer member 4 while the first corotron 1 will deliver negative ion charging current to the surface of the transfer member 4. Furthermore, since no point in the circuit between the first and second corotrons 1 and 2 and the high potential power source 3 is grounded, the positive ion charging current delivered by the second corotron 2 to the moving surface of the transfer member 4 must be exactly equal at any given instant to the negative ion charging current delivered to such surface by the negatively connected first corotron 1, in the same manner as set forth in U.S. Letters Pat. No. 3,244,083, supra. Additionally, as the current path established from the coronode 6 through the interconnected shields 8 and 7 to the coronode 5 is effectively in parallel with an ion charging current path residing between each of the coronodes 5 and 6 and the surface to be charged, as represented by the transfer member 4, it will be appreciated that the ion charging current I_c delivered to the surface to be charged is given by the relationship that:

$$I_c = I_p - I_s,$$

wherein I_p is the current applied to the coronodes 5 and 6 while I_s is the current flowing in the shield. The current I_p applied to the coronodes 5 and 6 is supplied to the coronodes 5 and 6 by the constant current source formed by the high potential power source 3 in serial combination with the impedance means R_1 or a suitable alternative therefor as mentioned above. Therefore, the value of the current I_p applied to the coronodes 5 and 6 is essentially a constant with time as changes in the dynamic impedance exhibited by the first and second corotrons 1 and 2 due to ambient conditions will be small with respect to the resistance value of the impedance means R_1 as seen by the high potential power source. Thus, the value of current I_p applied to the coronodes 5 and 6 is in a range of from (50-400 μ A) and is maintained at essentially a constant value. In addition, as the shield current I_s present in the current path formed by the interconnection of the shields 7 and 8 through the current limiting impedance means R_2 is small, being preferably limited in value as aforesaid to a range of from 1-10 μ A/in., of corotron and in any event since the

current limiting impedance means R_2 exhibits a value which is exceedingly large, i.e., 100-500 M Ω , as stated above, with respect to the dynamic impedance of the first and second corotrons 1 and 2 so that the impedance exhibited by the shield current path will be essentially constant despite changes in the dynamic impedance of the corotrons 1 and 2; the value of current I_s flowing in the current path between the shields 1 and 2 will be small and essentially constant in magnitude. Therefore, as both the value of current I_p applied to the coronodes 5 and 6 and the current flow I_s between the shields 7 and 8 are constant in value, it will be seen that the value of charging current I_c delivered to the surface to be charged yielded by the expression:

$$I_c = I_p - I_s$$

will be essentially constant in value. Accordingly, it will be seen that the paired corotron charging configuration illustrated in the Figure not only applies charging current of equal magnitude and opposite polarity to the surface to be charged at each instant of the operation, but in addition thereto, the value of charging current delivered to the surface to be charged by the first and second corotrons 1 and 2 will be essentially constant. This means that regardless of the spacing between the corotrons 1 and 2, the second corotron 2 will apply a positive ion charging current to the surface to be charged whose magnitude is constant in value and the first corotron 1 will apply a negative ion charging current to the surface to be charged whose magnitude is precisely equal to the constant value of the positive charging current delivered by second corotron 2. Thus, the instant invention allows the practical results achieved by connecting a pair of corotrons to opposite terminals of a floating supply to approach the theoretical advantages predicted because as variations in the ion charging currents delivered to a surface to be charged are avoided, exact magnitudes of neutralizing ion current will always be supplied to the surface to be charged by the second corotron of the pair regardless of the spacing between the pair of corotrons and the time interval between the application of successive charges. In addition, the maintenance of the current flowing in the shield preferably within a range of of corotron (1-10 μ A/in.) is highly desirable because, as described in more detail in my copending application Ser. No. 108,302, ion current flow may be initiated from the first and second corotrons 1 and 2 with a lower threshold voltage applied thereto and large portions of the ion charging current produced at the coronodes 5 and 6 may not be diverted to the shield and hence are delivered to the surface to be charged. This enables the first and second corotrons 1 and 2 to be operated in a highly efficient manner whereby sufficiently large magnitudes of charging current are delivered to the surface to be charged so that regardless of minor charge level variations thereon, the potential level associated with the corotron is imposed upon such surface to be charged.

When paired corotron apparatus according to the present invention is employed in an image transfer operation of the type indicated in the Figure, the negatively charged toner particles initially adhered to the surface of the photoreceptor 9 due to electrostatic forces of attraction are transferred to the adjacent surface of the transfer member 4 and thereafter the charge on the transfer member 4 is neutralized in the manner detailed below. Prior to receiving charging current from either of the first and second corotrons 1 and 2, the transfer member 4 disposed on the surface of the photoreceptor 9 is in physical contact with the toner image at only a few points on the surface thereof due to the absence of a strong force of attraction between adjacent surfaces of the transfer member 4 and photoreceptor 9 while the remaining portions of the lower surface of the transfer member 4 may be separated from the toner image on the photoreceptor 9 by an air gap of several microns. When, however, the successive portions of the photoreceptor 9 having the transfer member 4 disposed thereon are displaced under the second corotron 2, which under the conditions assumed above for a negative toner produces positive charging current, the appropriate portion of the transfer

member 4 in a charging relationship with the second corotron 2 will be subjected to a bombardment of positive ions along the width thereof which seek to impose the potential of the second corotron 2 on the appropriate surface portion of the transfer member 4. The positive charges applied to the surface of transfer member 4 will migrate to the opposite surface thereof adjacent to the toner image and hence will induce negative charges in corresponding portions of the conductive backing or substrate of the photoreceptor 9. The charge on the portions of the transfer member 4 receiving positive ion charging current from the second corotron 2 will produce a very substantial force of attraction between corresponding portions of the adjacent surfaces of the transfer member 4 and the photoreceptor 9 thereby bringing such portions of the transfer member 4 into intimate contact with the portions of the toner image on the adjacent portions of the photoreceptor. When these conditions obtain, the field strength between the charged portion of the transfer member 4 and the adjacent portion of the photoreceptor 9 will be sufficient to cause most of the negatively charged toner to be transferred from the photoreceptor 9 to the transfer member 4 as indicated in the Figure for the portions of the transfer member 4 and the photoreceptor 9 directly under and to the left of the second corotron 2. This operation will be continued for successive portions of the transfer member 4 on a continuous or discontinuous basis until the entire toner image has been transferred to the transfer member 4.

Prior to the invention set forth herein and that disclosed in U.S. Letters Pat. No. 3,244,083, supra, it was conventional to remove the transfer member 4 from the photoreceptor 9 subsequent to the transfer of the toner image by a peeling operation or the like. Because the transfer member 4 being formed of paper, plastic or the like is generally a relatively fair insulator, the charge thereon tended to remain essentially constant as the transfer member 4 was removed so that the potential thereof would increase linearly with separation. When the separation between the transfer member 4 and the photoreceptor 9 reached a distance equal to about (20 μ), the air gap therebetween would break down resulting in a discharge taking place between the transfer member 4 and the photoreceptor 9. This discharge would leave, under the conditions specified herein, a positive charge on the surface of the photoreceptor 9 and substantially destroy or distort the latent electrostatic image formed thereon so that such image was no longer suitable for secondary uses if desired.

With the paired corotron apparatus according to the present invention, however, successive portions of the transfer member 4 and the photoreceptor 9 are brought into a charging relationship with the first corotron 1 subsequent to the charging and image transfer step accomplished by the second corotron 2. The first corotron 1, as aforesaid, will subject the portions of the transfer member 4 successively brought into a charging relationship therewith to a negative charging current whose magnitude is precisely equal to the positive charging current then being delivered to subsequent portions of the transfer member 4 by the second corotron 2. Furthermore, as the first and second corotrons 1 and 2 produce essentially uniform currents according to the teachings of this invention, the negative ion charging current applied to successive portions of the transfer member 4 will be equal in magnitude to the positive ion charging current applied to these same portions of the transfer member 4 by the second corotron 2 during the preceding toner image transfer step. Thus, as successive portions of the transfer member pass beneath the first corotron 1, the charge thereon will be precisely neutralized in the well-known manner whereby the electrostatic relationship which is present between the transfer member 4 and the photoreceptor 9 is restored to that which obtained prior to the charging operation carried out by the second corotron 2 which resulted in image transfer. Therefore, subsequent to the charging operation carried out by the first corotron 1, the transfer member 1 may be easily removed from the photoreceptor 9 without discharge occurring therebetween so

that attendant destruction or distortion of the latent electrostatic image on the photoreceptor 9 is avoided. Thus, the latent electrostatic image on the photoconductor 9 may be reused or retained for possible later use.

5 Therefore, it is seen that the instant invention provides methods and apparatus for operating paired corotrons which are oppositely connected to a common power supply in a manner such that substantially uniform charging currents which are equal in magnitude but opposite in polarity are obtained. Accordingly, the present invention allows image transfer or tacking and stripping operations to be performed while the deleterious electrostatic discharge normally attending the removal of the tacked or image transfer member is avoided.

15 Although the present invention has been disclosed in conjunction with a specific exemplary embodiment thereof, various alternatives and modifications to the specific structure set forth herein will be obvious to those of ordinary skill in the art.

20 For instance, multiple coronode corotron structure could readily be substituted for the single coronode corotrons illustrated while corotron configurations employing multiple pairs of corotrons are readily available. Additionally, due to the high efficiency in the manner in which the corotrons disclosed

25 herein are operated, substantially larger values of delivered charging current are available and hence copying apparatus employing the instant invention may be operated at speeds which are higher than previously available or alternatively if it is desired to retain conventional operating speeds, lower value

30 potential sources may be used in apparatus according to the

teachings of the invention contained herein. Furthermore, as

will be appreciated by those of ordinary skill in the art, the

specific values and circuit parameters set forth herein are to

be viewed only as exemplary and not in a limiting sense.

35 While this invention has been described in connection with an exemplary embodiment thereof, it will be understood that many modifications will be readily apparent to those of ordinary skill in the art; and that this application is intended to cover any adaptations or variations thereof. Therefore, it is manifestly intended that this invention be only limited by the

claims and the equivalents thereof.

What is claimed is:

1. In a charging circuit for applying opposite polarity ion charging currents to a surface to be charged, said charging circuit including first and second corotron means disposed in a charging relationship with said surface to be charged and each of said first and second corotron means including coronode means for producing said ion charging current and shield means associated with said coronode means, wherein the improvement comprises:

50 constant current source means connected at a first polarity terminal thereof to a coronode means of one of said first and second corotron means and connected at a second polarity terminal thereof to said coronode means of another of said first and second corotron means, said constant current source means being isolated from any external reference potential other than those associated with connections to said first and second polarity terminals thereof; and

55 means for interconnecting said shield means of each of said first and second corotron means.

2. The improved charging circuit according to claim 1 wherein said means for interconnecting said shield means of each of said first and second corotron means comprises current limiting impedance means connected between said shield means of each of said first and second corotron means.

60 3. The improved charging circuit according to claim 2 wherein said current limiting impedance means exhibits a value of resistance which is large compared to the dynamic impedance exhibited between said coronode means and said shield means of each of said first and second corotron means.

4. The improved charging circuit according to claim 3 wherein said current limiting impedance means exhibits a value of resistance sufficient to limit current flow

therethrough to a small fraction of the current value applied to each of said coronode means by said constant current source means.

5. The improved charging circuit according to claim 4 wherein said constant current source means comprises high 5 potential power supply means serially connected to high impedance circuit means, said serially connected high impedance circuit means exhibiting a value of resistance which is substantial compared to the dynamic impedance exhibited by said first and second corotron means.

6. The improved charging circuit according to claim 5 wherein said current limiting impedance means exhibits a value of resistance sufficient to limit current flow therethrough to a range of one to ten microamperes per inch of corotron length.

7. The improved charging circuit according to claim 6 wherein said current limiting impedance means exhibits a value of resistance equal to or greater than the resistance exhibited by said serially connected high impedance circuit means.

8. A method of applying opposite polarity ion charging currents to a surface to be charged comprising the steps of:

10 disposing first and second corotron means in an appropriate charging relationship with said surface to be charged, each of said first and second corotron means including coronode means for producing said ion charging currents and shield means associated with said coronode means; connecting said coronode means of one of said first and second corotron means to a terminal of a constant current source means exhibiting a first polarity and connecting said coronode means of another one of said first and second corotron means to another terminal of said constant current source means exhibiting a second polarity; and

15 interconnecting said shield means of said first and second corotron means.

9. The method of applying opposite polarity ion charging currents to a surface to be charged according to claim 8 wherein the step of interconnecting said shield means of said first and second corotron means is accomplished by connecting current limiting impedance means between said shield means of said first and second corotron means.
